MEANS FOR CONNECTING BRACELETS
TO WRIST WATCHESLouis E. Valcourt, East Providence, R. I., assignor
to Kestenman Bros. Mfg. Co., Providence, R. I.,
a corporation of Rhode Island

Application July 25, 1950, Serial No. 175,702

3 Claims. (Cl. 24—265)

1

This invention relates to an improved spring-pin connector for attaching the ends of a strap, bracelet or the like to the lugs on a wrist-watch case.

More particularly, the improvement consists in providing a spring-pin connector which is adjustable to adapt it for use with wrist-watches having different spacing widths between the lugs on different types of watchcases.

One object of the invention is to provide a spring-pin connector embodying adjustable extension elements which may be set at different distances apart to provide different widths of spacing between their pintles which engage in the holes in the lugs on watchcases of various sizes.

Another object is to provide a device of the type indicated in which the adjustable extension elements are adapted to telescope within a hollow barrel on the holding member at the end of the strap or bracelet with detent-means for latching or locking said elements in their adjusted relationship.

Another object is to provide a device of the type indicated having adjusting means for the extension elements which is easy and convenient to manipulate for setting the pintles on said elements in spaced relationship at varying distances apart to fit different types of watchcases to which the strap or bracelet is to be attached.

Another object is to provide a device of the type indicated in which the complete assembly of the holding member and spring-pin is of artistic and neat appearance with the mechanical elements enclosed and concealed from view.

Another object is to provide an adjustable spring-pin connection which is of simple construction, economical to manufacture, and proof against derangement or getting out of order so as to be efficient and durable in use over long periods of time.

Further objects of the invention are set forth in the following specification which describes a preferred form of construction of the adjustable spring-pin connector with one modification thereof is illustrated by the accompanying drawing. In the drawing:

Fig. 1 is a plan view of one type of wrist-watch having widely spaced lugs on its case and illustrating the ends of a bracelet attached thereto by means of the improved spring-pin connector of the present invention;

Fig. 2 is a similar view showing a wrist-watch of different design having the lugs on its case spaced in closer relationship and illustrating the

2

ends of the bracelet attached thereto by the present improved spring-pin connector;

Fig. 3 is an enlarged plan view of the end member for the bracelet showing the present improved spring-pin with the pintles of its extension elements projecting therefrom to adapt them for connection to the lugs of a watch such as shown in Fig. 2;

Fig. 4 is a similar view showing the parts of the device in section and illustrating the extension elements of the spring-pin as spaced at a greater distance apart to adapt it for use with a watchcase such as shown in Fig. 1;

Fig. 5 is a bottom plan view of the end member illustrated in Fig. 4 shown with its cover swung back or opened to release the latching means for the extension elements of the spring-pin to adapt them to be adjusted at different distances apart;

Fig. 6 is a transverse sectional view of the device taken on line 6—6 of Fig. 5 and also illustrating the bottom cover of the device as swung open to release the latching means;

Fig. 7 is a similar sectional view showing the cover of the device closed to latch or lock the adjustable extension elements of the spring-pin in adjusted relationship;

Fig. 8 is a view showing a modified form of construction of the improved device with the parts illustrated in closed relationship;

Fig. 9 is a transverse sectional view of the same showing the cover open with the latching or locking means for the extension elements released;

Fig. 10 is a similar sectional view showing the cover closed to lock the extension elements of the device in their adjusted relationship; and

Fig. 11 is a part-sectional view taken on line 11—11 of Fig. 9 showing certain parts of the modified form of device.

As before indicated, a conventional method of attaching straps, bands and bracelets to wrist-watches consists in providing a so-called spring-pin at each end of the bracelet having telescopic pintle elements extensible under the action of a spring for engaging them in the perforations or holes in the lugs on the opposite sides of the watchcase. In wrist-watches of different shape and design the size of the case varies considerably and in men's watches, especially, the lugs on the case are spaced at a greater distance apart than on other watches of the same type or on watches of the type shown in Fig. 2 of the drawing. In these circumstances it has heretofore been generally impracticable for the jeweler or other retailer who sells the watchstrap or bracelet to fit it to all types of watches. Consequently, it was

necessary to stock several different types of watch-bands or bracelets to provide end members of different widths suitable for attachment of the bracelet to watches of different type and design. This required that the retailer stock a large number of bracelets having end members of different widths, thereby increasing his inventory and overhead expense and rendering it more difficult to satisfy all customers possessing watches of different size and shape.

It is therefore an object of the present invention to provide end-members for bracelets of a preferred type and width with adjustable spring-pins adapted to fit between and engage in the holes in the lugs on watches of different shape and size. For this purpose the present invention provides and end member for bracelets of standard size embodying convenient means for adjusting the spring-pins carried by such member to fit a bracelet to watches of different size having a wide range of spacing between the lugs on the cases.

Referring to the drawing, the present invention may be embodied in an end member for flexible bracelets of a popular type shown in Figs. 1 and 2 and comprising a series of expandable links to adapt it to fit wrists of different size. The end member 2 itself may be of conventional box-like form and shaped substantially to the contour of the links of the bracelet, that is, with a portion 3 having a crowned top wall 4 corresponding to that of the links 6 of the bracelet. The end member 2 may be constructed of sheet-metal shaped by a stamping operation or formed in suitable dies. As herein shown, the end member 2 is provided with pivot-means 5 on its hollow under side for connecting it with the expansion links 6 of the bracelet, see Figs. 5 and 6. Such means may include a flanged extension 7 projecting from the portion 3 of the end member 2 and carrying the pivots for connection with the expansion links 6 of the bracelet.

The forward portion of the end member 2 is constructed in the form of a tube of rectangular cross-section constituting the barrel 8 for telescopically mounting the spring-pin. The spring-pin comprises two tubular extension elements 10 carrying slidable blocks 11, see Fig. 4, having pintles 12 projecting therefrom for engagement with the holes in the lugs on the wrist-watch case. The pintle blocks 11 are preferably of solid construction with the pintles 12 projecting from their ends. As shown in Figs. 1 to 7, inclusive, the slidable pintle members or blocks 11 are of rectangular or square shape to adapt them to slide within the ends of the adjustable extension elements 10 which are also slidable in the square-shaped tubular barrel 8 of the end member 2. The extension elements 10 of the device may be constructed of sheet-metal folded into rectangular or square shape in cross-section with one end closed but formed with an opening for the pintles 12 on the blocks 11 to project outwardly therethrough.

A helical spring 15 extends longitudinally within the barrel 8 with its ends engaging against the pintle blocks 11 as shown in Fig. 4 to maintain the latter normally pressed against the closed ends of the slidable extension elements 10; while also tending to force the extension elements apart by sliding them longitudinally of the barrel 8. A relatively short length of round rod 16 is inserted through the coils at the central portion of the spring 15 whereby to prevent the spring from

being distorted or bowing out laterally when it is contracted as shown by the dotted lines in Fig. 3. The ends of the rod 16 are projected into the interior of the hollow extension elements 10 when the latter are retracted into the ends of the tubular barrel 8 as indicated in Fig. 3.

It will be understood that the extension elements 10 provide the means for adjusting the spacing between the pintles 12 in proportion to the width of the opening between the lugs on the watchcase whatever the width of such spacing within a relatively wide range. For latching or locking the extension members 10 in adjusted relationship to regulate the spacing between the pintles 12, manually-operable means are provided as next described. A hinged cover 20 is provided on the under side of the hollow portion 3 of the end member 2 with the latching means constituted as a part thereof so that when the cover is closed it will fixedly hold the extension members 10 in their adjusted relationship.

The cover 20 consists in a flat plate having hinge-ears 21 bent around to enclose a hinge-pin 5 reaching across the width of the end member 2 within its hollow portion 3 and riveted through the side walls thereof as shown in Figs. 4 to 7, inclusive. The cover 20 is thus hinged to close against the bottom of the section 3 of the end member 2 as shown in Fig. 7, or to swing open therefrom as illustrated in Fig. 6. A curved lip 23 projects from the forward edge of the cover 20 to provide for the insertion of the fingernail thereunder as a convenience for opening the cover. The forward end of the cover 20 is extended in a strip or flange projecting at right-angles thereto and cut away at intervals to form it into a series of blades or tines spaced apart to provide a plurality of openings or slots therebetween. As shown in Fig. 5, there are two relatively wide blades 25, one at each end of the cover 20, two narrower blades 26 spaced inwardly therefrom to provide slots 28. Next, there are two pairs of narrower blades or tines 29 and 30 with the tines 29 spaced laterally from the narrower blades 26 to form slots 31 and the inner tines 30 spaced from the tines 29 to provide slots 32.

The side wall of each extension member 10 is continued at the end to form a tab 35 which is bent outwardly at right-angles in the form of a blade adapted to engage in the different slots 28, 31 and 32 for fixedly holding the extension members in adjusted position. That is to say, after the extension elements 10 have been adjusted with the pintles 12 projecting from their ends in proper spaced relationship for engaging in the holes of the lugs on the watchcase the extension elements are held by the operator's fingers and the cover 20 swung into closed position, as shown in Fig. 7, to engage the blades 35 in the appropriate slots between the tines at the edge of the cover. For example, with the extension members 10 projected from the ends of the barrel 8 for their widest adjustment, see Figs. 4 and 5, the blades 35 will be positioned for engagement in the slots 28 when the cover is closed for locking the extension members fixedly in position. When, however, less width of spacing between the pintles 12 on the extension members 10 is desired, to adapt them for engagement with the more closely spaced lugs on a watchcase, the extension members 10 may be pushed into the barrel 8 against the tension of the spring 15 and held manually while the cover 20 is closed to engage the blades 35 in the slots 31 to lock

the parts in this relationship. As a further adjustment for watches with more closely spaced lugs the extension members 10 may be pushed further into the ends of the barrel 8 and held so that the detent blades 35 may be engaged in the slots 32 to adjust the pintles 12 in somewhat closer relationship. A still further adjustment for the pintles 12 is provided by pushing the extension elements 10 into the barrel 8 until their outer ends become flush with the ends of the barrel, as shown in Fig. 3, at which juncture the cover may be closed to engage the blades 35 with the inner sides of the tines 30 whereof to hold the extension elements in their closest spaced relationship. In this way four different adjustments are provided which adapts the ends of the spring-pin to be arranged for engaging the pintles 12 with watchcase-lugs spaced $\frac{5}{8}$ ", $\frac{11}{16}$ ", $\frac{3}{4}$ " or $\frac{7}{8}$ " apart, this including practically all types and sizes of watches at present in use. It will be understood that the bracelet to which the end member 2 is attached may be of any particular width, but the preferred type now popular is an expansion bracelet $\frac{5}{8}$ " in width and the present improved end member and spring-pin are particularly adapted for this conventional style. It should be noted that the several tines on the cover 20 are slightly curved or of arcuate shape as shown in Figs. 6 and 7 to adapt them to slide across the end of the bottom wall 9 of the barrel 8 in frictional engagement therewith for retaining the cover closed against the bottom of the end member.

It will be understood that with the extension elements 10 locked in adjusted position as above explained the pintles 12 may be pressed inwardly at their ends by sliding the blocks 11 against the pressure of the spring 15. The two-part spring-pin can be inserted between the lugs on the watchcase by holding the pintles 12 telescoped into the extension elements 10 and then by adjusting the end member 2 to register the pintles with the holes in the lugs the spring 15 will cause them to snap into the holes. In other cases, it may be more convenient to simply retract the extension elements 10 into the ends of the barrel 8 of the end member 2 without engaging their locking means and then after the pintles 12 have been engaged in the holes in the lugs on the watchcase the end members may be centered between the lugs and the cover 20 closed to engage the detent blades 35 with the appropriate slots to lock the end elements in fixed relationship. With either method of attaching the end members of the bracelet to the lugs on the watchcase the present improved device provides a secure fastening to prevent accidental release of the pintles from the holes in the lugs due to the fact that the extension elements are locked against retraction.

In the modified form of the device illustrated in Figs. 8 to 10, inclusive, the general construction and arrangement of the parts are substantially the same as first described. There is one difference in that the arrangement of the latching or locking means is the reverse of that first explained. In the modified construction the end member 40 is formed with a cylindrical barrel 41 by bending an extension of the top wall 42 into a partly open tube of circular cross section. The extension elements 43 are also of cylindrical shape with their ends closed by crimped portions formed with openings for the pintles 45 to project under the urging of a spring 46, shown partly in Fig. 8 as pressing

against the pintle blocks 47 which are mounted to slide in the extension elements. The part-cylindrical barrel 41 encloses a relatively thin walled bushing 48 within which the extension elements 43 are mounted to slide freely and urged to project from the ends of the barrel 41 under the expansion of the spring 46, previously mentioned.

At the inner end of each extension element 43 is a radial lug or square pin 50 suitably fastened in the wall of the extension element with its outer end projecting through a longitudinal slot 49 in the bushing 48. The pins 50 extend outwardly from the bushing 48 in position to engage in notches or slots cut into the edge of the circular portion of the barrel 41; it being noted that the barrel is open across a major portion of its width. Each lug or pin 50 projects through this opening beyond the periphery of the barrel 41 a sufficient distance to adapt it to be engaged by the operator's finger for moving the pins into engagement with the notches in the edge of the wall of the barrel. It will be understood that since the pins 50 on both expansion elements 43 project through the longitudinal slot 49 in the bushing 48, see Fig. 11, the bushing will be rotated by moving either pin to thereby effect simultaneous movement of the opposite pin. In this way the pins 50 on both extension elements 43 may be engaged in the appropriate slots after the extension elements have been adjusted in the desired relationship by the movement of one of the pins.

A series of slots in the edge of the barrel 41 are located with the proper spacing therebetween to provide dimensional adjustments of the extension elements similar to those previously explained. For example, there may be two slots 51 widely spaced toward the ends of the barrel 41 and two sets of closely-spaced slots 52 and 53 for narrower spacing of the extension elements 43. With the lugs or pins 50 engaged in the outermost slots 51 the extension elements 43 will be held projected at the maximum distance outwardly from the ends of the barrel 41 with their pintles 45 in the widest spaced relationship for engagement with the lugs on watches of a type such as shown in Fig. 1. When the extension elements 43 are retracted into the ends of the barrel 41 to provide for narrower spacing of the pintles 45 the two pins 50 may be engaged with the notches 52 or 53 to secure an adjustment to adapt the pintles 45 to be engaged in the holes of lugs of narrower spacing.

In this last-described form of construction of the device the extension elements are locked in adjusted position engaged in the slots at the edge of the barrel 41 by means of a hinged cover 55 similar in some respects to that previously described but without the spaced blades or tines for forming slots in the cover. On the contrary, the edge of the cover 55 is straight except for a curved lip 56 at its center as a convenience for opening the cover. With the cover 55 open as shown in Fig. 9 the extension members 43 may be slid in the bushing 48 to bring their pins 50 into register with any of the notches 51, 52 or 53 in its edge so as to adjust the pintles 45 in proper relationship for engagement with the lugs on several different types of watchcases. After the pins 50 have been inserted in the appropriate slots in the edge of the barrel 41 the cover 55 is closed to engage its edge against the pins to hold them in the slots and posi-

tively lock the extension elements in fixed relationship. As the cover 55 is closed its edge engages frictionally with the pins 50 to prevent its accidental release. A pair of projections 57 at the ends of the cover 55 are adapted to engage across the side walls of the end members 40 to limit the closing movement of the cover.

It will be observed from the foregoing specification that the present invention provides a device of great convenience for attaching straps, bands and bracelets to wrist-watches having cases of different design and dimensions. By use of the present device embodying a spring-pin of adjustable length for watches having their lugs set at many different distances apart many types of watches may be fitted with the same type of band or bracelet and the connections made by the jeweler or other salesman without requiring mechanical fitting as it is usually necessary to remove the end members from the bracelet and apply different ones thereto; or to carry bracelets of several different sizes in stock for attachment to different types of watches.

While the invention is herein illustrated and described as embodied in a preferred form of construction and one modified form thereof, it is to be understood that variations may be made in the structure and arrangement of the parts of the device without departing from spirit or scope of the invention as expressed in the appended claims. Therefore, without limiting myself in this respect, I claim:

1. Means for attaching straps, bands and bracelets to wrist-watches embodying an end member for connection to the end of a strap or bracelet, extension elements telescopically supported in said end member to adapt them to be projected outwardly from the ends thereof, pintles slidably supported in said extension elements, a spring engaging between said pintles to project them outwardly at the ends of the extension elements, an element hinged to said end member and provided with a series of spaced slots, detent projections on the extension elements engageable in said slots in the hinged element to hold said elements in different positions of spaced-apart relationship, and means

for releasably holding said hinged element in position with the detent means engaged in its slots.

2. In a device of the type specified, a housing member for attachment to the ends of a bracelet, extension elements telescopically held in said housing to adapt them to be projected at different distances from the ends thereof, pintles slideable in said extension elements, a spring engaging between the pintles to maintain them projected outwardly from the ends of the extension elements, detent means projecting laterally from said extension elements, a cover hinged to the housing, said cover formed with a series of tines spaced apart to form slots for engagement by the detent means on the extension elements to hold the latter in adjusted spaced-apart relationship, and frictionally-engageable means between the cover and housing member for retaining the cover in closed relationship to lock the detent means in selected slots therein.

3. In a device of the type indicated, a housing member for connection to the end of a bracelet, said housing member provided with a hollow barrel, extension elements fitted to slide in the interior of the barrel, pintles slideable in the extension elements for projection from the ends thereof, a spring extending between the extension elements and engaging the pintles to slide them in said elements, detent means projecting laterally from the ends of said extension elements, and a cover hinged to the housing, said cover having projecting portions spaced along its edge with slots therebetween adapted to be engaged by the detent means on the extension elements to hold them in adjusted spaced-apart relationship to adapt the pintles for engagement with watchcase lugs spaced at different distances apart.
